JOHN M. CRAWFORD, OF PHILADELPHIA, PENNSYLVANIA.

Letters Patent No. 66,221, dated July 2, 1867.

IMPROVED BRIDLE-BIT.

The Schedule referred to in these Letters Patent and making part of the same.

TO ALL WHOM IT MAY CONCERN:

Be it known that I, JOHN M. CRAWFORD, of Philadelphia, in the county of Philadelphia, and in the State of Pennsylvania, have invented certain new and useful improvements in Riding and Driving Bridle-Bits; and I do hereby declare that the following is a full, clear, and exact description thereof, reference being had to the accompanying drawing, forming a part of this specification.

Figure 1 is a perspective view of my invention.

Figure 2 is a vertical section through the "bit" and "cheek-pieces."

The nature and operation of my invention will fully appear from the following description.

A is the bit or piece which enters the horse's mouth. B B' are "cheek-pieces," fastened loosely to the ends of the bit A by means of screws C C. These cheek-pieces are provided with slots *a*, so as to have a sliding movement upon the screws C. H H are rings, passing through the lower ends of the cheek-pieces, to which the driving-reins D are attached in the usual manner. The upper ends of the cheek-pieces are provided with rings *b*, to which the cheek-strap F is attached. G G' are rings passing through the ends of the bit A. To these rings are attached the bearing or check-rein E.

In operating my invention, the bridle is placed upon the horse's head in the usual manner, and the bit in his mouth, the bit resting upon the screws at the bottom of the slots in the cheek-pieces, as shown in fig. 1. When the horse becomes restive or unmanageable, or grasps the bit between his teeth, it is only necessary to pull strongly upon the driving-rein D, which will cause the bit A to be forced upward in the slots in the cheek-pieces, thereby forcing the bit upward in the horse's mouth, and disengaging it from the grasp of his teeth. When in this position, the cheek-pieces become nearly horizontal instead of vertical. If it be desirable to have the bit so arranged as to require a stronger force to cause the bit A to rise in the slot, all that will be necessary will be to change the relative positions of the two cheek-pieces B and B', by taking out the screws. When it is desirable to use the bit as an ordinary bit, I remove the cheek-pieces altogether and affix the cheek-straps F, as well as the driving-rein D, to the rings H. My improved bit may be used for riding, driving, and "bitting" bridles. The slots *a*, in the cheek-pieces, may be made straight instead of curved, as shown in the drawing. When the horse has the habit of bearing hard upon the check-rein, it can be removed from rings G, and fastened to rings H. This arrangement is suitable for "bitting" horses. When desirable, the driving-rein D can be fastened to the rings G G'.

What I claim as new, and desire to secure by Letters Patent, is—

1. The slotted cheek-pieces B B', either curved or straight, when attached to a bridle-bit, substantially as and for the purposes set forth.
2. Making the cheek-pieces capable of being reversed, by acting in combination with bit A and screw C, substantially as and for the purposes set forth.
3. The combination and operation of the bit A, screws C, and cheek-pieces B, with the cheek-strap F, and reins D and E, substantially as and for the purposes set forth.

In testimony that I claim the above-described invention, I have hereunto signed my name this 21st day of February, 1867.

JOHN M. CRAWFORD.
